GUN CHARGER

Walter R. Weeks, Hamden, Conn., assignor to
 General Electric Company, a corporation of
 New York

Application April 21, 1944, Serial No. 532,953

5 Claims. (Cl. 89—1)

My invention relates to gun chargers, more particularly to mechanism for automatically recharging or reloading a machine gun in the event that it fails to fire, and has for its object a simple and reliable mechanism for disabling the gun charger mechanism after it has operated for a plurality of times.

My present invention is an improvement over the invention of a copending application Serial No. 447,327, filed by Alexander C. Wall on June 17, 1942, and assigned to the same assignee as this application. The invention of the Wall application was made prior to my invention and is to be regarded as prior art with respect to this present application.

In carrying out my invention I provide an electric motor operating at a substantially constant speed for driving two timer devices for controlling the charger mechanism. One timer device is connected in a high speed 1:1 driving ratio with a shaft driven by the electric motor and operates in the event of failure of the gun to fire to effect operation of the charger mechanism. The movable member of this timer is connected to the driving shaft through a friction coupling and means are provided operated by the firing of the gun for pushing this member back each time the gun fires. In the event that the gun fails to fire, the member continues to operate and in a very short predetermined interval of time sets the charging mechanism in operation.

The other timer is driven in a predetermined low speed driving ratio with the motor driven shaft through a special mechanical gearing. The actuating member of this timer also is connected to the driving gearing through a friction coupling, and also is pushed back to a starting position each time the gun fires. In the event that the gun does not fire, the actuating member of this timer continues to move and, after a predetermined time interval, is moved far enough to operate switching mechanism to disable the charger. The actuating member is pushed back to its starting position manually in order to put the charger back into service.

For a more complete understanding of my invention reference should be had to the accompanying drawings, Fig. 1 of which is a plan view of charger timing mechanism embodying my invention; Fig. 2 is a side elevation view of the device shown in Fig. 1; Fig. 3 is an end elevation view looking from the left to the right of Fig. 1; Fig. 4 is a view showing the timer mechanism of Figs. 1, 2 and 3 assembled in a complete charger device, some parts of which are shown diagram-

matically; Fig. 5 is a diagrammatic view showing the electric control circuits for the charger; Fig. 6 is an enlarged exploded view in perspective of the timer mechanism; Fig. 7 is a diagrammatic view showing details of operation of the gearing; while Fig. 8 is a perspective view of typical firing apparatus.

Referring to the drawings, I have shown my invention in one form as providing two side metal supporting plates 10 and 11 for supporting, as well as partly enclosing, the timer mechanism. These two plates are secured together in suitable spaced relation at their left-hand ends by screws 12 and 13 securing the plates to a spacing member 14. Also, the plates are secured together by screws 15 and 16 passing through them. Mounted between the plates is an electric driving motor 17 which is preferably a suitable direct current type arranged to be operated from a storage battery. This motor carries a worm 18 (Fig. 6) on its shaft which meshes with a worm wheel 19 mounted on substantially the center of a bushing or sleeve 20 constituting a drive shaft. The sleeve 20 is in turn rotatably mounted on a stationary rod 20a extending through the sleeve 20 and having its ends projecting from the ends of the sleeve and mounted rigidly in suitable supports 21 and 22 secured to the side plates 10 and 11.

Referring particularly to Fig. 6, the sleeve or drive shaft 20 is connected through a friction coupling 23 to a high speed timer control member or arm 24. This friction coupling may consist, as shown in Fig. 3, of two discs or washers 25 and 26 loosely surrounding the sleeve 20 on the right-hand side of the worm gear 19 and in engagement with opposite sides of a hub portion of the arm 24, this hub portion being provided with an aperture through which the sleeve 20 loosely extends. It will be noted that the portion of the sleeve 20 on the right-hand side of the worm gear (Fig. 6) has a considerably larger outside diameter as compared with the left-hand portion. Adjacent the ring 26 is a ring 27 which is secured rigidly to the sleeve 20 and adjacent the ring 25 is a ring or disc 28 which is secured to the sleeve against rotation but slidable along the sleeve. These discs and the hub of the arm 24 are compressed tightly together by means of a spring washer 29 mounted between the disc 28 and a washer 30 bearing against the nut 31 on the sleeve 20. This assembly thus provides a friction clutch between the sleeve 20 and the arm 24.

The purpose of the arm 24 is to operate, by

means of its projection 32 engaging the end of a pivoted operating arm 33, a suitable single pole, double throw snap switch 34 to its circuit closed position, whereby a circuit for the coil 75 is closed by its contacts 34a (Fig. 5) to cause the charger to operate. The contacts 34b, forming a part of the switch 34, are at the same time opened to open the circuit of the firing solenoid 76. In the event that the gun fires as usual, however, a cocking stud 35 carried by the bolt of the gun moves back and engages the lower end of a resetting arm 36 having its upper end pivoted on the sleeve 20, whereby the lever or arm 36 is moved back for a predetermined distance in a clockwise direction, as seen in Fig. 6. During this movement a resetting latch member 37 carried by the lever 36 engages a projection 38 on the operating arm 24 and moves the arm 24 back in a clockwise direction to a starting position. It will be understood that the motor 17 drives the sleeve 20 and the lever 24 in a counterclockwise direction, as seen in Fig. 6.

For the purpose of disabling the charger after the charger has operated to recharge the gun for a predetermined time interval during which it has recharged the gun a predetermined number of times, I provide a second timer control member or arm 40 similar in shape to the arm 24, which arm is connected through a high ratio speed reducing gearing 41 to the drive sleeve 20 so as to operate at a predetermined low speed. This arm 40 is provided with a projection 42 which is engaged by the resetting latch 37 each time the gun fires, whereby the arm 40 is returned to a starting position in the same manner as the arm 24. However, when the driving means or operating plunger 43 of the charger moves the stud 35 and the breach mechanism of the gun to the reloading position, the plunger itself engages a lever 44 mounted on a stationary pivot 45 so as to lift the lever, i. e., turn it clockwise as seen in Fig. 6. The movable end of the lever 44 which extends loosely through an aperture 46 in the resetting latch 37 then lifts the latch 37 above the projection 42 so that the latch when moved back does not reset the arm 40. Thus the arm 40 continues to be driven under these conditions by the motor and eventually an arm 47 forming a part of it operates a lever 48 pivoted on a stationary pivot 49 and thereby operates a single throw, double pole switch 50 of a suitable snap type to disable the charger. This switch 50 is provided with two pairs of contacts (Fig. 5), normally closed contacts 50a and normally open contacts 50b. When the switch is operated, contacts 50a open to disable the charger while contacts 50b close thereby closing a circuit for the firing solenoid 76 across the contacts 34b which are now open. Thus by closing the firing switch 88, the firing solenoid can be energized for firing of the gun independently of contacts 34b in the event that the gun gets back into working condition from any cause, such as vibration.

The driving gear 41 comprises an internal gear 51 which is secured rigidly to a sleeve 52 through which the sleeve 20 extends, the sleeve 52 being mounted on the sleeve 20 for rotation. Inside of this internal gear 51 is a pinion 53 which is somewhat smaller in diameter than the internal gear 51 and is provided with a central aperture 54. In this aperture 54 is an eccentric or cam 56 secured to the sleeve 20.

Also secured to the outer side of the pinion 53 are four pins 57, 58, 59, and 60 which are spaced equal distances apart and lie on a circle con-

centric with the center of the pinion 53. These pins extend parallel with the shaft 20 each into an enlarged circular recess in the side plate 11. Three of these recesses 61, 62, and 63 are shown in Fig. 1 of the drawings, the fourth being shown in Fig. 7. These recesses are equally spaced with respect to each other and are arranged with their centers lying on a circle which is concentric with the sleeve 20, and which circle has the same diameter as the circle on which lie the centers of the pins. The size or diameter of the recesses is just sufficient to provide for the radial movement of the gear 53 imparted to it by the cam 56 when the sleeve 20 rotates, i. e., the freedom of movement of each pin in its recess is substantially equal to twice the eccentricity of the eccentric or cam 56. Thus, as the sleeve and cam rotate, the gear 53 is oscillated in its own plane but is held against rotation by the engagement of the pins with the walls of the recesses in the side plate 11. Actually each pin moves around the side wall of its recess once each turn of the sleeve 20.

As the sleeve 20 is turned counterclockwise, as seen in Fig. 6, by the motor 17, the eccentric cam 56 tends to turn the pinion 53 clockwise, but since the pinion is held against rotation by the pins, the internal gear is turned counterclockwise through an angle measured by the number of teeth it has greater than the pinion. In other words, in one rotation of the cam the pinion oscillates and returns to its original position but in running over the teeth of the internal gear it has engaged only its own number of internal gear teeth. In a typical device I have provided an internal gear with forty-eight teeth and a pinion having forty-four teeth. With this combination the internal gear was turned counterclockwise each revolution of the sleeve 20 through an angle represented by four teeth, i. e., $\frac{1}{12}$ of one revolution.

At any instant one or more of the pins is applying a force sufficiently normal to the wall of its recess to hold the pinion 53 against rotation. Thus, in the four angular positions of the cam 56 with its high point adjacent one of the pins, the two pins on a diameter at right angles with the diameter of the one pin are normal to the walls of their respective recesses. One of these two normal pins tends to move against its wall and thereby holds the pinion from rotation. Fig. 7 is a diagrammatic representation showing the relative positions of the pins and recesses for the relative positions of the parts shown in Fig. 6. At this time the high point of the cam 56 is directly adjacent the lowermost pin 60 and the pinion is in its lowermost position with the pins each in engagement with the lowermost point of the wall of its recess. Since the pinion tends to rotate counterclockwise, the pins 58 and 60 cannot prevent this rotation because their bearing surfaces are tangential with the walls of their recesses. But the pins 57 and 59 are normal to their recess walls, and since the pin 57 tends to move against its wall, the pin 57 holds the pinion against rotation.

This condition of one pin normal to its recess wall and preventing rotation exists, as pointed out above, for the four positions of the cam with its high point adjacent each of the four pins. For intermediate positions, it will be obvious that two or more of the pins are sufficiently normal to their recess walls to prevent rotation of the pinion. For example, when the high point of the cam is half way between the pins 59 and 60, the two pins 57 and 60 will have radii normal to their recess walls,

which radii extend at 45-degree angles with the direction in which the pins tend to move. Therefore, these two pins apply components of force to their recess walls in directions normal to the walls whereby the pins are held against rotation. At this time, the pins 58 and 59 are in corresponding positions with respect to their recess walls but they tend to move away from their walls. This is the position in which the direction of rotation of the pinion is least normal to any one of the recess walls. In other intermediate positions, some one of the pins is more nearly normal to its recess wall in the direction of rotation of the pinion.

This gearing provides a very compact, rugged and lightweight gearing having a high driving ratio, and with a constant ratio giving uniform output velocities. The gearing is described and claimed in my copending divisional application, Serial No. 591,351, filed May 1, 1945.

The operating arm 40 is mounted by means of a friction clutch 40a similar to the clutch 23 on the sleeve 52 so as to be driven frictionally by the sleeve.

As shown, the arm 36 is made in two parts 64 and 65 which embrace the worm wheel 19 and which are provided with slots 66 and 67 near their lower ends through which the reset latch member 37 extends loosely. The two arms 64 and 65 are joined together to provide a single arm 36 which extends through a slot 68 in the fluid cylinder 69 for the piston 43 into the path of the stud 35. It will be understood that the assembled device, as seen in Fig. 4, with the fluid piston 43 and control mechanism, is suitably secured by studs or bolts to one side of the machine gun so that the cocking stud 35 on the machine gun extends through two slots 70 and 71 extending lengthwise in the cylinder. The piston 43 in the cylinder preferably is operated by a compressed fluid such as CO₂ gas, the container for which may be connected to an inlet pipe 72 leading to a suitable valve 73 from which the gas is supplied to the cylinder through a duct 74. The valve 73 is normally closed to the gas supply and it is opened to admit compressed gas to the cylinder by energization of the solenoid 75 controlled by the normally open switch contacts 34a.

The firing solenoid 76, when energized, pulls a plunger 77 (Fig. 8) toward the right hand whereby a pin 78 is moved toward the right hand to a firing position. As shown, the plunger operates two arms 79 on shafts 80 and 81 whereby the shafts are turned. On the lower ends of the shafts 80 and 81 are forked arms 82 and 83 arranged to cooperate respectively with a single projection 84 on the pin 78 and a pair of projections 85 on the pin 78. Thus the arm 83 between the projections of the pair 85 moves the pin 78 back and forth while the projection 84 engages the arm 82 when the pin 78 is moved to its extreme left hand position. This construction provides for reversal of the pin 78 in accordance with the side of the gun on which the charger is mounted. As seen in Fig. 5, when the plunger 78 is in its right-hand firing position, it engages a latch member 86 which normally holds the firing pin 87 and pushes the latch 86 toward the right hand thereby to release the firing pin and effect firing of the gun. It will be understood that the firing pin 87 and the latch 86 are carried by the movable breech block of the gun. The pin 78 is in such a position that just as the breech block reaches its fully closed position the pin is engaged by the latch and the latch moved to release the firing pin.

Referring further to Fig. 5, the electric circuits

of the charger are controlled by a normally open push button 88, a circuit leading from the push button through a normally closed switch 50a and then to three parallel circuits, one leading through the motor 17, another through the contacts 34b of switch 34 and the coil 76, and a third through contacts 34a of switch 34 and the coil 75. The contacts 50a and 34b are normally closed, as shown.

In the operation of the charger when the gun is to be fired, the gunner pushes the push button 88 to its closed position and holds it closed during the continuance of the firing. Closure of the button 88 energizes the timer motor 17 and energizes the coil 76 which moves the stud 78 to its firing position and immediately fires the gun. At the moment of firing, the cocking stud 35 is in the position shown in Figs. 4 and 6. During the firing operation it moves toward the left hand to its reloading position and in its movement engages the arm 36 and moves it toward the left to reset the arms 24 and 40, i. e., push them back clockwise, as seen in Fig. 6, to starting positions each time the gun is fired. In the event that the gun fails to fire, which would be caused by a dead cartridge or exhaustion of the supply of cartridges, the cocking stud 35 remains in the firing position of Figs. 4 and 6, and the timer motor then moves the arm 24 to close the switch contacts 34a and energize the coil 75, while at the same time opening the switch contacts 34b to deenergize the coil 76. The energization of the coil 75 opens the valve 73 and admits compressed gas to the cylinder 69 whereby the plunger 43 is caused to move toward the left hand, as seen in Figs. 4 and 6, and thereby move the stud 35 to its fully cocked or reloading position. This movement of the stud 35 of course resets the arm 36, as previously described, and resets the arm 24 whereby the switch 34 is operated to reopen contacts 34a and reclose contacts 34b. The deenergization of the coil 75 closes the valve 73 thereby to shut off the supply of gas and also exhaust the gas from the cylinder 69. The plunger 43 is thereupon moved by a spring (not shown) back toward the right to its starting position. This allows the cocking stud and breech mechanism to reclose. During this operation the dead shell is ejected and a fresh shell inserted. This is assuming, of course, that the button 88 has been held depressed in its closed position. When the breech mechanism reaches its closed position the gun is fired, the coil 76 being energized through the reclosing of contacts 34b of switch 34 and the firing stud 78 being in firing position.

As previously explained, however, the cylinder 43 in advancing engages the lower side of the arm 44 and moves it upward thereby moving upward the reset latch far enough so that it does not engage the lower end 42 of the lever 40. Consequently, the lever 40 is not reset by operation of the charger plunger 43 and, assuming still that the button 88 is closed, the arm 40 is driven by the motor 17 without interruption during a number of operations of the plunger. Assuming that the gun does not fire until after the predetermined time interval, the arm 40 is operated far enough for its projection 47 to engage the arm 48 and open contacts 50a and close contacts 50b of switch 50. This deenergizes the motor 17 but reconnects operating coil 76, and also prevents energization of the coil 75 whereby the charger is disabled and firing of the gun is prevented until it has been serviced and a fresh supply of ammunition provided if required. In

order to put the gun charger back in service, the arm 48 is reset by moving it clockwise, as seen in Fig. 6, by depressing manually a button 94 connected to the arm through a wire 92.

While I have shown a particular embodiment of my invention, it will be understood, of course, that I do not wish to be limited thereto, since many modifications can be made, and I therefore contemplate by the appended claims to cover any such modifications as fall within the true spirit and scope of my invention.

What I claim as new and desire to secure by Letters Patent of the United States is:

1. A charging device for an automatic gun provided with a reciprocating cocking member comprising driving means arranged to engage the cocking member of the gun and effect movement thereof from a firing position to a reloading position and back to the firing position, a timer motor, two timer control members connected to be driven by said timer motor respectively at predetermined speeds, means operated by a first of said timer members when moved to a predetermined position for causing operation of said driving means, means operated by the second of said timer members when moved to a predetermined position for disabling said driving means after a plurality of operations of said driving means, resetting means arranged to be operated by the cocking member of the gun for moving each of said timer members to a predetermined starting position each time the cocking member moves to a reloading position, said timer members being driven at such speeds by said motor that each is reset by the cocking member during normal firing operation of the gun before the respective timer member has been moved to its determined position, and means operated by said driving means for disabling said resetting means for the second of said timer members when said driving means operates to move the cocking member whereupon said second timer member moves to its said predetermined position to disable said driving means.

2. A charging device for an automatic gun provided with a reciprocating cocking member comprising driving means provided with a reciprocating operating member arranged to engage the cocking member of the gun and effect movement thereof from a firing position to a reloading position and back to the firing position, a timer motor, two timer control members connected to be driven by said timer motor respectively at predetermined high and low speeds, means operated by said high speed timer member when moved to a predetermined position for causing operation of said driving means, means operated by said low speed timer member when moved to a predetermined position for disabling said driving means after a plurality of operations of said driving means, resetting means arranged to be operated by the cocking member of the gun for moving each of said timer members to a predetermined starting position each time the cocking member moves to a reloading position, said timer members being driven at such speeds by said motor that they are reset by the cocking member during normal firing operation of the gun before reaching said predetermined positions, and means operated by said driving means for disabling said resetting means for said low speed timer member when said driving means operates to move the cocking member whereupon said low speed timer member moves to its said predetermined position to disable said driving means.

3. A charging device for an automatic gun provided with a reciprocating cocking member comprising driving means arranged to engage the cocking member of the gun and effect movement thereof from a firing position to a reloading position and back to the firing position, a timer motor, two timer control members, a slip driving connection between each of said timer members and said timer motor whereby said timer members are driven respectively at predetermined speeds, means operated by a first of said timer members when moved to a predetermined position for causing operation of said driving means, means operated by the second of said timer members when moved to a predetermined position for disabling said driving means after a plurality of operations of said driving means, resetting means arranged to be operated by the cocking member of the gun for engaging and moving each of said timer members independently of said timer motor by the slipping of its said driving connection to a predetermined starting position each time the cocking member moves to a reloading position, said timer members being driven at such speeds by said motor that each is reset by the cocking member during normal firing operation of the gun before the respective timer member has been moved to its said predetermined position, and means operated by said driving means for disabling said resetting means for the second of said timer members when said driving means operates to move the cocking member whereupon said second timer member moves to its said predetermined position to disable said driving means.

4. A charging device for an automatic gun provided with a reciprocating cocking member comprising driving means arranged to engage the cocking member of the gun and effect movement thereof from a firing position to a reloading position and back again, a shaft, a motor connected to drive said shaft, two timer control arms rotatably mounted on said shaft, driving connections between said arms and said shaft for driving said arms respectively at predetermined speeds, means operated by a first of said arms when turned to a predetermined position for effecting the operation of said driving means, means operated by the second of said arms when turned to a predetermined position for disabling said driving means after a plurality of operations of said driving means, a resetting arm having one end rotatably mounted on said shaft and having its other end extending into the path of movement of the cocking member so as to be moved by the cocking member to a predetermined starting position each time the cocking member moves to a reloading position, a resetting latch member movably mounted on said resetting arm and normally biased to a position to engage said timer arms and move them to predetermined starting positions each time said resetting arm is moved by the cocking member, said timer arms being driven at such speeds by said motor that they are reset by the cocking member during normal firing operation of the gun before reaching said predetermined positions, and means engaged by said driving means for moving said latch member to a position in which it does not engage and reset said second timer arm when said driving means operates to move the cocking member whereupon said second timer arm moves to its predetermined position to disable said driving means.

5. A charging device for an automatic gun provided with a reciprocating cocking member comprising driving means provided with a re-

ciprocating operating member arranged to engage the cocking member of the gun and effect movement thereof from a firing position to a reloading position and back again, a shaft, an electric motor connected to drive said shaft at a substantially constant speed, two timer control arms rotatably mounted on said shaft, a slip driving connection between one of said arms and said shaft for driving said arm at a high speed, a slip driving connection between the other of said arms and said shaft including a speed reducing gearing for driving said other arm at a low speed, means operated by said high speed arm when turned to a predetermined position for effecting the operation of said driving means, means operated by said low speed arm when turned to a predetermined position for disabling said driving means after a plurality of operations of said driving means, a resetting arm having one end rotatably mounted on said shaft and having its other end extending into the path of movement of the cocking member so as to be moved by the

5 cocking member to a predetermined starting position each time the cocking member moves to a reloading position, a resetting latch member movably mounted on said resetting arm and normally biased to a position to engage said timer arms and move them through slippage of said driving connections to predetermined starting positions each time said resetting arm is moved by the cocking member, said timer arms being driven at such speeds by said motor that they are reset by the cocking member during normal firing operation of the gun before reaching said predetermined positions, and means engaged by said operating member for moving said latch member to a position in which it does not engage and reset said low speed timer arm when said driving means operates to move the cocking member whereupon said low speed timer arm moves to its predetermined position to disable said driving means.

WALTER R. WEEKS.
